UNITED STATES PATENT OFFICE.

THOMAS HUSTON, OF KOKOMO, INDIANA.

FARM-GATE.

1,341,905.

Specification of Letters Patent.

Patented June 1, 1920.

Application filed December 1, 1919. Serial No. 341,631.

To all whom it may concern:

Be it known that I, THOMAS HUSTON, a citizen of the United States, and a resident of Kokomo, in the county of Howard and State of Indiana, have invented certain new and useful Improvements in Farm-Gates, of which the following is a specification.

My invention relates generally to gates, and particularly to farm gates.

10 The purpose of my invention is the provision of a simple and inexpensive farm gate having means for holding one end of the gate in suspension, such means being adjustable to vary the height of the gate so as to permit the ready opening thereof under adverse conditions, such as when snow accumulates beneath the gate.

15 I will describe one form of gate embodying my invention, and will then point out the novel features thereof in claims.

20 In the accompanying drawings:—

Figure 1 is a view showing in side elevation one form of gate embodying my invention;

25 Fig. 2 is a top plan view; and

Fig. 3 is a vertical sectional view, taken on the line 3—3 of Fig. 1.

Similar reference characters refer to similar parts in each of the views.

30 Referring specifically to the drawings, A designates generally a gate comprised of horizontally disposed rails 15 which are held in parallel spaced relation by end rails 16 and 16^a. Associated with the rear end rail 16^a is a brace rail 17, and intermediate the ends of the rails 15 is a second brace rail 18.

35 The gate A is of the swinging type, and is braced in open or closed position by 40 means of posts P and P'. These posts P and P' are of rectangular formation in cross section and are arranged in different vertical planes at the same time being spaced apart so as to slidably accommodate the gate A. The upper ends of the posts are connected by short bars 19, such bars extending downwardly of the posts and being arranged in spaced parallel relation, as clearly shown in Fig. 2. The bars 19 support a suspension block B and permit lon-

45 gitudinal adjustment of the latter thereon through the medium of grooves 20, which are formed in the upper side of the bars and slidably receive the block B. As illustrated to advantage in Fig. 1, the block B is of substantially wedge-shape in side ele-

vation, its upper edge being inclined toward the forward end of the gate and provided at spaced intervals with notches 21. These notches 21 are adapted to receive a 60 wire loop W which passes around the block B and downwardly between the bars 19, with its lower end embracing a notch 22 formed in one of the rails 15.

From this arrangement, it will be seen 65 that the rear end of the gate is held in suspension by means of the wire loop W, and that the height of the rear end of the gate may be varied in accordance with the position of the upper end of the wire loop with- 70 in the block B. That is to say, if the wire loop reposes in the notch 21 at the thick end of the block, the gate A will be elevated to the maximum height to which this suspen- 75 sion means is capable of supporting the gate. However, as the wire loop is advanced toward the forward end of the block B, the rear end of the gate is lowered.

80 In the closed position of the gate A its forward end bears against a post P², the opposite sides of the latter being provided with plates 23 which lock the gate against lateral movement in its closed position. The lower end of the gate A rests upon a supporting plate 24, its rear end being 85 curved to facilitate the moving of the gate to its closed position. The gate is latched in closed position by means of a latch 25 which in the present instance comprises an L-shaped rod that is rotatably mounted 90 within the post P² and is adapted to embrace the end rail 16 thus preventing rearward movement of the gate with respect to the post P².

95 To balance the gate so that its lower edge I will normally lie in a horizontal plane, I provide a weight T which in the present instance is in the form of a box that is secured to the gate at a point rearwardly of the wire loop W, as shown in Fig. 1 100 and is adapted to be filled with a sufficient quantity of stone so that the weights upon opposite sides of the loop are made equal. This arrangement obviously reduces the wear of the movable parts and facilitates 105 the manipulation of the gate.

When it is desired to open the gate, the latch 25 is moved to releasing position and the gate is then pushed rearwardly, swing- 110 ing about the upper end of the wire loop W as a center. When the gate has been moved sufficiently to clear the plates 23, it

may then be swung laterally to the open position, it being understood that the relative positions of the posts P and P' permit this movement, and when the gate is 5 in the open position its sides will engage the confronting sides of the posts.

In order to facilitate the closing of the gate, or more particularly to facilitate the longitudinal movement thereof, so as to 10 engage the plates 23, the notch 22 is formed in its respective rail 15 at a point rearwardly of the upper end of the wire loop W so that the loop W is at all times disposed on an incline with relation to the 15 vertical. With this arrangement, the gate is caused to be biased toward the post P², thus materially assisting in the closing of the gate and effecting a proper seating of the same in its closed position.

20 Although I have herein shown and described only one form of gate embodying my invention, it is to be understood that various changes and modifications may be resorted to without departing from the 25 spirit of the invention or the spirit and scope of the appended claims.

Having thus described my invention, I claim:

1. In combination, a pair of spaced posts 30 disposed in different vertical planes, a gate working between said posts, and flexible means for holding one end of the gate in suspension comprising a wire loop and a notched block adjustable on said post.

35 2. In combination, a pair of posts, a gate working between said posts and including rails, one of which is formed with a notch, a block adjustably supported upon the upper end of said posts and formed with notches,

and a wire loop trained about said block 40 and said notched rail and disposed within one of the notches of said block in said rail.

3. In combination, a pair of posts, a gate 45 working between said posts and including rails, one of which is formed with a notch, a pair of spaced bars secured to the upper ends of said posts and formed with grooves, a block slidably fitted within said grooves and formed at spaced intervals with 50 notches, and a wire loop trained about said block and said notched rail and reposing within one of the notches of said block and the notch of said rail.

4. In combination, a pair of posts, a gate 55 working between said posts, a wedge-shaped block adjustable on said posts and formed at intervals with notches, said gate being formed with a notch and a wire loop trained about said block and said gate in a manner to engage one of the notches of said block and the notch of said gate.

5. In combination, a pair of posts, a gate 60 adapted to work between said posts, a pair of bars secured to the upper ends of said 65 posts and spaced apart and formed with grooves, a block of wedge shaped formation, having sliding fit within said grooves and notched on its upper edge at spaced intervals, and a wire loop embracing said 70 block and gate and interposed between said bars and adapted to be disposed within any one of said notches, said gate being formed with a notch at such a point so as to receive the lower end of said loop and to 75 cause the loop to assume an inclined position, for the purpose described.

THOMAS HUSTON.
